UNITED STATES PATENT OFFICE

123,646

DESIGN FOR A COMBINED PERFUME CONTAINER AND PENDANT

Falco di Verdura, New York, N. Y., assignor to Parfums Schiaparelli Inc., New York, N. Y., a corporation of New York

Application September 12, 1940, Serial No. 94,985

Term of patent 3½ years

To all whom it may concern:

Be it known that I, Falco di Verdura, a subject of the King of Italy, residing at New York city, in the county of New York and State of New York, have invented a new, original, and ornamental Design for a Combined Perfume Container and Pendant, of which the following is a specification, reference being had to the accompanying drawing, forming part thereof.

In the drawing

Fig. 1 is a front perspective view of a combined perfume container and pendant, showing my new design;

Fig. 2 is a rear perspective view thereof;

Fig. 3 is a top perspective view of same.

I claim:

The ornamental design for a combined perfume container and pendant, substantially as shown.

FALCO DI VERDURA.
